UNITED STATES PATENT OFFICE

96,915

DESIGN FOR A CELLULOSE DERIVATIVE PLASTIC SHEET OR SIMILAR ARTICLE

John Hill, Hillside, N. J., assignor to Celluloid
Corporation, a corporation of New Jersey

Application July 31, 1935, Serial No. 57,875

Term of patent 14 years

To all whom it may concern:

Be it known that I, John Hill, a subject of the King of England, residing at Hillside, county of Union, State of New Jersey, have invented a new, original, and ornamental Design for Cellulose Derivative Plastic Sheet or Similar Article, of which the following is a specification, reference being had to the accompanying drawing, forming part thereof.

In the accompanying drawing:

The figure is a plan view of a cellulose derivative plastic sheet or similar article showing my new design.

The thickness of the sheet or similar article is not material. The dominant feature of the ornamentation of the sheet or similar article shown on the drawing is not only the arrangement of the alternating strata but the pleasing effect produced by the fact that colored strata alternate with strata having differential luster pearl effects.

I claim:

The ornamental design for a cellulose derivative plastic sheet or similar article, substantially as shown and described.

JOHN HILL.
